TWO TEMPERATURE REFRIGERATOR

George K. Iwashita, Indianapolis, Ind., assignor,
by means assignments, to Admiral Corporation,
Chicago, Ill., a corporation of Delaware

Application July 14, 1943, Serial No. 494,629

12 Claims. (Cl. 62—95)

1

This invention relates to refrigerators and particularly to refrigerators of the type having two compartments or portions maintained at different temperatures.

An object of the invention is to provide an improved two-temperature refrigerator.

Another object of the invention is to provide an improved refrigerator of the type having primary and secondary refrigerant circuits.

Another object of the invention is to provide an improved two-temperature refrigerator having primary and secondary refrigerant circuits.

Yet another object of the invention is to provide a refrigerator of the type having primary and secondary refrigerant circuits, wherein circulation of the refrigerant in the secondary circuit is maintained without employing pumps or the like as a means for forcing the refrigerant through the circuit.

Yet another object of the invention is to provide an improved refrigerator having a complete refrigerating system including compressor, condenser, and evaporator, which is conveniently removable as a unit from the refrigerator cabinet for servicing.

Other objects and advantages of the invention will become apparent during the description, reference being had to the accompanying drawings, wherein:

Fig. 1 is a front view of a refrigerator of the two-temperature type;

Fig. 2 is a vertical section showing the interior arrangement of the refrigerator of Fig. 1;

Fig. 3 is a section taken through a refrigerator having a modified arrangement;

Figs. 4 and 5 illustrate further modifications of the invention;

Fig. 6 is a close-up illustrating certain details of the modification shown in Fig. 5; and

Figs. 7, 8 and 9 illustrate still further embodiments of the invention.

As illustrated in Figs. 1 and 2, the refrigerator comprises a cabinet 12, liners 14 and 16 supported therein by means of breaker strips 18 and insulated from the cabinet by means of insulation 20, a machinery compartment 22 housing a compressor and condenser, and a door normally sealing the interior of the liners 14 and 16, having an outer shell 24 and metal panels 26 and 28 insulated therefrom and arranged to close the front ends of the liners 14 and 16, respectively. A rubber gasket 30 seals the interior of the liners when the door is closed. The upper liner 14 forms a food storage compartment which is maintained at a cool temperature, but preferably above the dew point, while the lower liner 16 forms a freezing compartment, sometimes referred to as a frost chest.

A primary refrigerating system associated with the refrigerator includes the sealed motor-compressor unit 32 and the condenser 34 positioned in compartment 22. In addition, the primary system or circuit includes upper and lower coils 36 and 38 which constitute heat absorbing evaporators. The outlet of condenser 34 is connected by means of a capillary tube 40 to the upper coil 36. A conduit 42 having a pressure reduction valve 44 connected therein leads from the outlet of coil 36 to the inlet of coil 38. Conduits 46 and 48 connect the inlet and outlet, respectively, of the compressor to coil 38 and condenser 34.

The upper evaporator coil 36 is mounted on a thin heat conducting metal plate 50 in the upper portion of the refrigerator cabinet, and the lower evaporator coil 38 is likewise mounted on a thin heat conducting metal plate 52. As illustrated, both coils 36 and 38 are serpentine in form and lie flat against the respective plates.

A closed secondary circuit containing a volatile liquid refrigerant is associated with the upper liner 14, and comprises an evaporator portion 54 wrapped around the top, sides and back of liner 14, and a condenser portion 56 which is a coil mounted on a thin heat conducting metal plate 58. The plate 58 is secured by suitable means to plate 50 on which the evaporator coil 36 of the primary circuit is mounted. A downwardly extending conduit 60 connects the low side of condenser portion 56 of the secondary system with the low side of the evaporator portion 54. Another connecting conduit 62 slants upwardly from the upper end of the evaporator portion 54 to the top of the vertical condenser coil 56.

Another secondary circuit is associated with the lower liner 16. This circuit comprises a condenser portion 64 mounted on a flat heat conducting metal plate 66, an evaporator portion 68 wrapped around the top and bottom, sides and rear of liner 16, a conduit 70 connecting the condenser portion 64 with the low side of the evaporator portion 68, and an upwardly slanting conduit 72 connecting the upper side of the evaporator portion with the condenser coil 64. The plate 66 is secured by suitable means to the plate 52.

In operation of the refrigerator, refrigerant vapor compressed by the compressor 32 is first circulated to condenser 34 where it is cooled and liquefied. Subsequently it passes through capillary tube 40, wherein it is prevented from ex-

panding by the restricting effect of the tube, to evaporator 36, wherein it begins expansion. The expansion of part of the liquid to the gaseous state in evaporator 36 absorbs heat through the heat transfer plates 58 and 62 from the condenser coil 56 of the upper secondary circuit. The refrigerant of this secondary circuit which is thus liquefied in the condenser portion 56 drains to the bottom of conduit 60 whence it enters the evaporator portion 54 of the secondary circuit and comes into heat exchange relationship with the walls of liner 14. The refrigerant in evaporator portion 54 expands, withdrawing heat from liner 14 and from the interior of the compartment and passes upward through said evaporator portion under its natural impulse to rise as it becomes vaporized. Finally, the refrigerant in the secondary circuit rises through conduit 62 to condenser coil 56 whence it is again liquefied to return to the evaporator portion.

The refrigerant in the primary system, leaving evaporator 36 in a partially expanded state, passes through the pressure reduction valve 44 which maintains a pressure differential between the two primary system evaporators 36 and 38, in order to maintain a predetermined temperature differential between the upper and lower liners of the refrigerator. The refrigerant is permitted to expand fully in the evaporator coil 38 and its evaporation absorbs large amounts of heat through the heat transfer plates 66 and 52 from the condenser coil 54 of the lower secondary circuit. The refrigerant in the lower secondary circuit is thus liquefied in condenser portion 64 and is then carried by conduit 70 to the low side of the evaporator portion 68, where it evaporates, withdrawing heat from liner 16 and the interior thereof, and passing gradually upward through the coil toward conduit 72 and the condenser where the cycle begins again. The vaporized refrigerant in the primary system is drawn into the intake side of compressor 32 through conduit 46, and is then compressed to begin the primary cycle.

In general, the lower compartment is maintained at a low temperature and a low relative humidity, whereas the upper compartment is maintained at a higher temperature and a higher humidity to serve a somewhat different purpose in the storage of foods.

It will be apparent that the refrigerator arrangement described provides secondary means for cooling the compartments of the refrigerator wherein the flow of the refrigerant is obtained without the need of pumps or the like to force circulation, and the primary circuit is so arranged as to be readily removed from the cabinet for repair or replacement. It will be noted that the primary evaporator coils 36 and 38 are not particularly deeply imbedded in the insulation 20. The refrigerator is provided with a removable rear panel 14 to permit removal of the primary evaporator coils 36 and 38. In removing, the plates 58 and 62 are loosened from the plates 56 and 66, respectively, the compressor 32 is loosened from its support, and the entire primary system is taken out. Repair of the system may then be accomplished in a central service station having the necessary facilities. By positioning the condenser coils of the secondary circuits vertically as shown, the necessity for a trap to prevent draining of the condensate back through the evaporator portion is avoided. In both instances the evaporator portions of the secondary systems are disposed substantially wholly below

their condensers in order that the circulation in the secondary systems will be satisfactorily maintained. The secondary system evaporators, which are wrapped around the respective liners 14 and 16 and are therefore deeply imbedded in the insulation, will not need to be removed from the refrigerator at any time.

In the modified embodiment of the invention shown in Fig. 3, the primary refrigerant circulating circuit has a single evaporator coil 88 which is in heat transfer relationship with the condensers of two secondary circuits. The outlet side of the primary system condenser is connected by means of a capillary tube 90 to the inlet of evaporator coil 88, and the evaporator outlet coil 92 is connected to the inlet of the primary system compressor. One of the two secondary circuits comprises an evaporator coil 94 in heat transfer relationship with the lower liner 16, and the condenser 96 in heat exchange relationship with the evaporator coil of the primary system and mounted between metal plates 100 and 106 which confine both the condenser coil of the secondary system and the evaporator coil of the primary system. The other secondary system comprises an evaporator portion 102 in heat transfer relationship with the liner 14, and a condenser portion 104 in heat transfer relation with the evaporator portion 88 of the primary system by means of a metal plate 106 on which the condenser 104 is mounted, and by means of suitable spacer elements 108 which are confined between plates 106 and 88. Because the condenser 96 of the secondary system which cools liner 16 is in direct heat exchange relation with the evaporator of the primary system, whereas the condenser 104 of the secondary system which cools the liner 14 is in heat exchange relation with the primary evaporator through the spacers 108, the desired temperature differential between compartments 14 and 16 may be maintained by choosing spacers 108 of the proper type and size to maintain the heat exchange rate of compartment 16 above the heat exchange rate of compartment 14, according to the desired ratio.

This arrangement simplifies the primary system, since it requires a single primary evaporator. It has the same advantages, that the primary system is easily removable for servicing and that the secondary system is so arranged as to have a constant circulation of refrigerant according to the principles of fluid flow. Furthermore, the need for a pressure return valve like the valve 44 of Fig. 2 is avoided by using the spacers 108 to maintain the proper differential in temperature between the upper and lower compartments.

In the refrigerator shown in Fig. 4, the compartments are inverted, with the freezing compartment 16 in the upper portion of the refrigerator and the higher temperature higher humidity compartment 14 in the lower part of the refrigerator cabinet. The restricted tube 98 which leads from the condenser of the primary system is connected to the lower primary evaporator 110, which is in heat transfer relation with the condenser 112 of a secondary system having an evaporator 114 in heat exchange relation with the liner 14, the primary evaporator 110 and the secondary condenser 112 being confined between plates 116 and 118, the inner plate of which is spaced from the wall of the liner 14. A short length of capillary tube 120 which prevents complete expansion of the refrigerant in the lower primary evaporator coil connects the outlet of said coil to the inlet of the upper primary evaporator

coil 122. This upper primary evaporator 122 is confined between the wall 124 of liner 16 and a plate 126, and is in heat exchange relation both with the liner wall and with the condenser 128 of a secondary circuit which includes an evaporator portion 130 in heat exchange relation with the sides, rear and bottom of liner 16. The effect of capillary tube 120 and the spacing of the evaporator coil 110 from liner 14 cooperate to maintain a temperature differential between the compartments 14 and 16.

In the refrigerator of Figs. 5 and 6, the primary circuit has a single evaporator coil 132 in direct heat exchange relation with the liner or frost chest 16. The coils of the evaporator 132 are secured to the walls of liner 16 by means of metallic Permagum 134. The liner 16 is supported at the rear by a nonheat conducting block 136, and is removably held in position by means of a tensioned strapping 138 which can be disconnected at 140 to permit removal of the liner. The condenser coil 142 of a secondary circuit having an evaporator coil 144 in heat exchange relation with liner 14 is removably mounted on the side of the liner 16 by means of a bracket 146. The condenser 142 of the secondary system is therefore in heat exchange relation with the walls of liner 16 and through them with the evaporator 132 of the primary system. The primary evaporator thus directly cools the frost chest 16 and at the same time cools the refrigerant in the secondary system in order that said secondary system may withdraw heat from liner 14. In order that the cooling of liner 14 may be improved, the space between the lower wall of liner 16 and the upper wall of liner 14 is left uninsulated, allowing transfer of heat from the lower liner to the upper liner by convection. The removable panel 148, provided in the rear of the refrigerator cabinet for removing the frost chest and the primary evaporator is relatively small, and the restricted tube 90 and return conduit 92 are outside the refrigerator body for the greater part of their length. As in the other embodiments of the invention, the primary system is removable for servicing and the slope of the secondary coils is such that the proper flow of refrigerant is obtained. The primary refrigerating system may be removed from the cabinet by removing the panel 148, withdrawing the insulation between the back of the liner 16 and the panel 148, opening the connection at 140, and releasing the bracket 146. The coils of the secondary system are spread outwardly slightly to permit the low temperature compartment liner and the evaporator coils, which are secured thereto, to be withdrawn through the opening which is normally closed by the panel 148.

In the modification shown in Fig. 7, the primary system is provided with two evaporators, including an upper evaporator 150 which is in heat exchange relation with the condenser 152 of a secondary system, which has an evaporator portion 154 in heat exchange relation with the higher temperature compartment 14. The other evaporator coil 156 of the primary system is in direct heat exchange relation with the low temperature liner 16, the evaporator being coiled around the top, bottom, sides and rear of said liner. With this arrangement no dual pressure control valve is required inasmuch as the pressure differential between liners 14 and 16 may be obtained through the direct contact of primary evaporator coil 156 with liner 16 as against the provision of a secondary system intermediate the primary evapora-

tor 150 and the liner 14. The coils of the lower primary evaporator 156 are not fixedly secured to liner 16, but instead are so arranged that the primary system may be removed for servicing without disturbing said liner.

In the refrigerator of Fig. 8, the primary system is provided with two evaporators. The upper evaporator 158 is in direct heat exchange relation with the frost chest 16, and the lower evaporator 160 is in heat exchange relation with a metal container 162 which is filled with a eutectic brine 164. The evaporator 160 maintains the brine at a low temperature and the brine in turn cools the walls of liner 14.

In the refrigerator of Fig. 9, the primary circuit is again provided with an upper evaporator 158 in direct heat exchange relation with the frost chest 16 and a second evaporator portion 166. In this case, the heat exchange between the liner 14 and evaporator 166 is accomplished by circulation of air around the liner 14, there being no insulation around the surface of liner 14. In order to improve air circulation a fan 168 driven by an electric motor 170 may be used to blow air across the coils of the primary evaporator. The need for a secondary circuit is thus eliminated entirely.

Although several embodiments of my invention have been described, it will be apparent to those skilled in the art that numerous other modifications might be derived without departing from the fundamental principles of the invention. It is, therefore, my intention that the terms of the following claims should constitute the only limitation in scope of the invention disclosed.

I claim:

1. In a refrigerator having a lower low temperature compartment and an upper higher temperature compartment, a secondary refrigerant circulating system having an evaporator portion in heat exchange relation with the upper compartment and having a condenser portion above said evaporator portion, a separate secondary refrigerant circulating system having an evaporator portion in heat exchange relation with the lower compartment and having a condenser portion above the associated evaporator portion, and a closed primary refrigerating system having an upper evaporator in heat exchange relation with the condenser of the first secondary system and a lower evaporator in heat exchange relation with the condenser of the second secondary system.

2. In a refrigerator having two compartments maintained at different temperatures, a secondary refrigerant circulating system having an evaporator portion in heat exchange relation with one of said compartments and having a condenser portion, a separate secondary refrigerant circulating system having an evaporator portion in heat exchange relation with the other compartment and having a condenser portion, and a closed primary refrigerating system having an evaporator constructed and arranged for ready removability and maintained in heat exchange relation with the condenser of one of the secondary systems and a second evaporator constructed and arranged for ready removability and maintained in heat exchange relation with the condenser of the other secondary system.

3. In a refrigerator having two compartments maintained at different temperatures, a secondary refrigerant circulating system in heat transfer relation with one of said compartments, another secondary refrigerant circulating system in

heat transfer relation with the other compartment, and a closed primary refrigerating system including an evaporator portion having a coil removably maintained in heat transfer relation with one of the secondary systems, a second coil removably maintained in heat transfer relation with the other secondary system, means connecting the coils of the evaporator, and a pressure reduction control valve in said connecting means, whereby a higher pressure may be maintained in one of the evaporator coils than in the other.

4. In a refrigerator having two compartments maintained at different temperatures, a secondary refrigerant circulating system in heat transfer relation with one of said compartments, another secondary refrigerant circulating system in heat transfer relation with the other compartment, and a closed primary refrigerating system including an evaporator portion having a coil removably maintained in heat transfer relation with one of the secondary systems, a second coil removably maintained in heat transfer relation with the other secondary system, and means connecting the coils of the evaporator, said connecting means having means whereby a higher pressure may be maintained in one of said coils than in the other.

5. A refrigerator comprising a liner forming a relatively high temperature, high humidity compartment, a secondary refrigerating system having a part in heat transfer relation with said liner, a second liner forming a low temperature compartment, and a sealed primary refrigerating system including an evaporator portion having a part thereof removably maintained in heat transfer relation with a condenser part of the secondary refrigerating system, and another part thereof connected in series of the first part and removably maintained in heat transfer relation with the low temperature compartment liner.

6. In a refrigerator having a lower low temperature compartment and an upper higher temperature compartment, a secondary refrigerant circulating system having a heat absorbing portion in heat exchange relation with the upper compartment, and a primary refrigerating system having a heat absorbing section, a portion of which is in heat exchange relation with the secondary circuit at a point above the heat absorbing portion of said secondary circuit, and a portion of which is in heat extracting relation with the lower compartment, said portions of the primary heat absorbing section being connected in series.

7. In a refrigerator having a lower low temperature compartment and an upper higher temperature compartment, a secondary refrigerant circulating system having a heat absorbing portion in heat exchange relation with the upper compartment, and a primary refrigerating system having a heat absorbing section, a portion of which is in heat exchange relation with the secondary circuit at a point above the heat absorbing portion of said secondary circuit, and a portion of which is in heat extracting relation with the lower compartment, said portions of the primary heat absorbing section being connected in series, and means for causing the circulation of refrigerant in the primary circuit.

8. A refrigerator comprising a liner forming a low temperature compartment, a liner forming a higher temperature compartment, a secondary refrigerating circuit in heat transfer relation with the higher temperature compartment liner, and a closed primary refrigerating system including an evaporator having a coil removably maintained

5 in heat transfer relation with the secondary circuit and a coil removably maintained in heat transfer relation with the low temperature compartment liner, the difference in effectiveness between the direct contact of the latter evaporator coil with the low temperature compartment and the connection between the former evaporator coil and the higher temperature compartment through the secondary refrigerating circuit serving to maintain a temperature differential between the two compartments.

9. A refrigerator comprising a liner which forms a low temperature compartment, a second liner spaced from the first liner which forms a higher temperature compartment, means thermally insulating said liners from each other, a secondary refrigerant circulating system having a heat absorbing portion in heat exchange relation with the higher temperature compartment liner and having a condenser portion, a primary refrigerant circulating system having an evaporator coil, said primary evaporator coil having a portion in heat absorbing relation with the low temperature compartment liner and another portion in heat absorbing relation with the condenser portion of the secondary system, and a thermally conductive member positioned between and in heat exchange relation with said secondary condenser and said second mentioned portion of said primary evaporator coil.

10. A refrigerator comprising a liner which forms a low temperature compartment, a second liner spaced from the first liner which forms a higher temperature compartment, a secondary refrigerant circulating system having a heat absorbing portion in heat exchange relation with the higher temperature compartment liner and having a condenser portion, a primary refrigerant circulating system having an evaporator coil, said evaporator coil having a portion in heat absorbing relation with the low temperature compartment liner and another portion in heat absorbing relation with the condenser portion of the secondary system, and a heat exchange contact plate in heat exchange contact with the primary evaporator and the secondary condenser to facilitate the heat transfer therebetween.

11. A multi-temperature, multi-compartment refrigerator comprising a first liner forming a food storage compartment, a second liner separated and spaced from said first liner and forming a second storage compartment, and a refrigerating means for extracting heat from said compartments and maintaining a temperature differential between said compartments, said means comprising a secondary refrigerating system having an evaporator portion in heat transfer relation with said first liner and having a condenser portion above said evaporator portion, and a sealed primary refrigerating system including an evaporator portion, said evaporator portion having a part arranged in direct heat exchange relation with said second liner and a second part removably maintained in heat exchange relation with said secondary system condenser portion, said secondary condenser portion and said second part of said primary evaporator being of convoluted form and being arranged in parallel planes, and a refrigerant liquefying means connected to said primary evaporator portion, said primary refrigerating system being of sufficient capacity for extracting the heat dissipated by said secondary condenser portion and by said second liner.

12. A multi-temperature, multi-compartment

refrigerator comprising a first liner forming a food storage compartment, a second liner separated and spaced from said first liner and forming a second storage compartment, means thermally insulating said liners from each other, and a refrigerating means for extracting heat from said compartments and maintaining a temperature differential between said compartments, said refrigerating means comprising a secondary refrigerating system having an evaporator portion in heat transfer relation with said first liner and having a generally flat coiled condenser portion above said evaporator portion, and a sealed primary refrigerating system including an evaporator portion, said evaporator portion having a first part arranged in direct heat exchange relation with said second liner and a second part removably maintained in heat exchange relation with said secondary system condenser portion, said second part of said primary evaporator portion having a generally flat coiled form, and a refrigerant liquefying means connected to said primary evaporator portion, said primary refrigerating system being of sufficient capacity for extracting the

heat dissipated by said secondary condenser portion and by said second liner.
